EYE EXERCISING MACHINE

Herman Katz, Oakland, Calif.

Application November 8, 1934, Serial No. 752,082
Renewed September 27, 1937

12 Claims. (Cl. 128—76.5)

The invention relates to machines arranged for exercising and thereby strengthening and developing the eye muscles and the various eye functions.

An object of the invention is to provide a machine of the character described which will afford a movable target for attracting the eyes over a variety of courses of movement which will fully and completely call upon and exercise all of the eye muscles.

Another object of the invention is to provide an eye exercising machine of the character described which will simultaneously exercise the focus or accommodation and the convergence functions of the eyes.

A further object of the invention is to provide an eye exercising machine of the above character which shall afford a stereoscopic arrangement to separate the vision of the eyes one from the other and to simultaneously exercise the eyes individually both as to angle or convergence and accommodation.

Still another object of the invention is to provide a machine of the character described which may through a variance of light intensity on the object to which the eyes are attracted, exercise and develop the muscles and nerves controlling the dilation and closing of the iris.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings:

Figure 1 is a front view of an eye exercising machine constructed in accordance with my invention and with the front plate thereof removed to show portions of the inner controlled mechanism.

Figure 2 is a vertical sectional view of the machine shown in Figure 1 taken substantially on the plane of the line 2—2 of Figure 1.

Figure 3 is a transverse sectional view taken substantially on the plane of the line 3—3 of Figure 1.

Figure 4 is a fragmentary longitudinal sectional view taken substantially on the plane of the line 4—4 of Figure 3.

Figure 5 is a front elevation of a part of the machine shown in Figure 1.

Figure 6 is a side elevation of the exercising machine adapted for stereoscopic exercise.

Figure 7 is an enlarged side elevation of a portion of the machine shown in Figure 6.

Figure 8 is a plan view of the machine parts shown in Figure 7.

Figure 9 is a back elevational view of the illumination switch means used in connection with the machine of my invention and shown with the back plate thereof removed.

Figure 10 is a fragmentary sectional view taken substantially on the plane of the line 10—10 of Figure 9.

Figure 11 is a schematic wiring diagram for the complete electric circuit used in connection with the machine.

The eye exercising means of the present invention consists of an observation unit such as a binocular eye-piece and a target and a supporting and motivating means for said target for moving the same in a plurality of predetermined paths relative to the observation unit. The latter means in accordance with the present invention is capable of reciprocating the target either longitudinally of the lines of sight of the eye-piece or across such lines of sight either horizontally or vertically or obliquely or along substantially any other line intersecting or paralleling or inclined to said lines of sight. Further the target supporting and motivating means is capable of moving said target through rotary or spiral paths with substantially any desired positioning of the plane of said paths relative to said lines of sight and being further effective to maintain a constant facing of said target during the course of its movement through any of the aforesaid paths. As another feature where stereoscopic binocular vision is desired, I provide for a septum which is so arranged and mounted relative to the eye-piece and target to move at one end with said target so as to maintain separated vision of the eyes and to divide the target proper into a pair of spaced target portions on which may be provided stereograms or the like. In this latter instance a pair of targets adapted for stereoscopic fusion are preferably provided on such portions.

In one of the important adaptations of the present machine, the plane of the target member is positioned at substantially right angles to the lines of sight of the observation unit and a stereoscopic binocular eye-piece is used for obtaining single binocular fusion of two targets carried on the target member and the target member is set in a rotary motion around the aforesaid lines of sight so as to simultaneously move the target in

the same direction and to the same extent at all times through closed paths. At the same time, the orienting means for the target described in the foregoing is effective to prevent the targets from rocking relative to each other and from overturning during movement thereof, so that they are normally maintained in a pre-selected position relative to each other, and are caused to move in such a manner that any straight line drawn on the surface of either target will move 10 into successive positions which are parallel with each other at all times, so that single binocular vision thereby may be maintained.

As illustrated in the drawings, the eye exercising machine of my invention comprises a standard 16 upon which is mounted for rotation a hollow arm 17 which in turn carries a target 18 for attracting the eyes. As here shown, the arm is mounted on the standard by interengaged bearing portions 19 and 21 secured to the arm and standard respectively and is rotatably driven by a motor 22 which is mounted on the top of the standard and which is provided with a gear 23 which engages a ring gear 24 on the arm.

As an important feature of my invention, the target is caused on rotation thereof with the arm to automatically turn as the same rotates so as to remain constantly upright or in other adjusted angular position at all times. Thus, notwithstanding the rotation of the target with the arm, any indicia or character carried by the target will at all times be maintained right side up and facing the patient for viewing. The means for so automatically turning the target, as may be best seen in Figures 2, 3, and 4, consist of a drive shaft 26 which extends lengthwise in the hollow portion of the arm 17 and which is rotated one complete revolution about its axis, on rotation of the arm 17 through one complete revolution, and the unit revolution of the shaft 26 is communicated to the target supporting shaft 27 by means of engaged bevel gears 28 and 29 having a one to one gear ratio. As here shown, rotation of the shaft 26 in conformity to the rotation of the arm 17 is effected, as may best be seen in Figures 1 and 2, by means of engaged bevel gears 31 and 32 having a one to one gear ratio and which are secured to the radially inner end of the shaft 26 and to the standard 16 at the axis of rotation of the arm respectively. Preferably the target 18 is secured to the supporting shaft 27 therefore by means of a hinge 33 which permits of the positioning of the target to face either parallel to the plane of rotation of the arm as shown in Figure 6 or at right angles thereto as shown in Figure 2. Thus, by reason of this arrangement and as will be readily understood, with the target arranged as shown in Figure 2 and with the patient seated approximately in the plane of rotation of the arm 17, the eyes of the patient will be attracted up and down vertically while the accommodation function of the eyes will be ever changing to focus the target at its constantly varying distance to the eyes. On the other hand with the target turned to face parallel to the plane of rotation of the arm 17 and with the patient positioned to the front of the machine, it will be clear that the eyes of the patient will be attracted to follow a circular path of the target, thus exercising both the transverse and vertical eye deflecting muscles while subjecting the focal length of the eye to but a small change.

As a further and important feature of my invention, the target 18 is arranged to be disposed at various radial positions on the arm 17 so as to

vary the course of movement of the eyes and is further arranged to be uniformly reciprocally moved over the length of the arm so as to inscribe further and advantageous courses of movement. 5 The means for moving the target along the length of the arm in the present machine comprises a carriage 35 which provides a bearing support for the target supporting shaft 27 and which is guided for longitudinal movement along the arm by means of a pair of spaced side guide rails 34 and which is arranged to be positively driven in its movement by a pair of threaded shafts 36 and 37. As may be best seen from Figure 1, the shafts 36 and 37 are driven through an appropriate gear mechanism 38 by means of an electric motor 39 carried at the inner end of the arm 17. A feature of the gear mechanism 38 is its arrangement as here shown to drive the shafts 36 and 37 in opposite directions and means are provided for causing the operative engagement of the carriage with first the shaft 36 for moving the carriage inwardly and then disengaging the shaft 36 and engaging the shaft 37 for moving the carriage outwardly. In the present embodiment, and as may be best seen from Figures 3 and 4, this means comprises a lever 41 which has a pivotal connection 40 intermediate its ends to the carriage and which is provided at each opposite end with a threaded nut segment 42 for threaded engagement with the shafts 36 and 37, and becomes so engaged as the lever is oscillated in opposite directions about the pivot 40, by a spring pressed toggle mechanism 43 mounted on the carriage. Means for deflecting the toggle member 43 to either side of the pivotal connection 40 of the lever so as to engage one of the segments 42 with one of the shafts 36 or 37 is here provided in the form of a pair of beveled projections 44 which extend in opposite longitudinal directions from the opposite ends of the lever 41 and which are positioned to engage and to be raised by a pair of adjustable stop members 46 carried on the guide rail 34. As will be seen from Figure 4, each of the members 46 are provided with a roller 45 which on approach of the carriage thereto engages and displaces the beveled end of the projections 44 to rock the lever about the pivot 40. This pivoting of the lever disengages the nut segment 42 from the screw 36 and causes the movement of the toggle mechanism to the other side of the pivotal point 40 to engage the opposite nut segment 42 with the screw 37 to start the outward movement of the carriage. Similarly as the carriage approaches the stop member 46 at the outer end of the arm the co-action of the projection 44 at the other side of the lever and the roller on the stop member 46, causes a reverse pivoting of the lever and the re-engagement of the nut 42 with the screw 36 to start the inward movement of the carriage. As will be thus understood, the stop members 46 in this manner define the end of the movement of the carriage 35 so that as great or as small a reciprocating movement of the target as is desired may be effected by merely spacing the stop members 46 an appropriate longitudinal distance from each other.

In order that the target may be caused to continue to turn in proportion to the rotation of the arm 17 so as to maintain a constant facing of the target as above explained and still be capable of longitudinal movement over the arm, I prefer to mount the bevel drive gear 29 for the target shaft 27 on the shaft 26 in a manner permitting slidable movement of the gear together with the

carriage 35 while causing the gear to rotate with the shaft 26. This provision has been here effected, as may be noted from Figures 3 and 4, by shaping the shaft 26 flat sided and by mounting the gear 29 on a sleeve 41 carried by the carriage and which while slidable on the shaft 26 is arranged to rotate therewith.

Preferably and as here shown, the inner operating mechanism in the arm 17 is covered and protected by a removable front plate 52 which, as may be noted from Figure 5, is provided with longitudinally slotted portions 53, 54, and 56 opposite the guide rails 34 and the centrally disposed shaft 26 for the extension through such slotted portions of the adjustable stop members 46 and the target supporting shaft 27.

In many instances it is desirable to confine the movement of the target so as to exercise but a single set of eye muscles. For this purpose, I prefer to hold the arm 17 in some fixed angular position and simply cause the longitudinal reciprocal movement of the target along the arm. For instance, the arm 17 may be fixed in a vertical position and the target moved up and down thereon so as to cause a simple raising and lowering of the eyes in following the target, or the arm may be fixed in a horizontal or some inclined position so as to cause the eyes to be moved transversely either horizontally or obliquely. In the present machine I may provide such an angular holding of the arm 17 against rotation by mounting on the standard 16 a spring pressed detent member 48 which releasably engages in a plurality of circumferentially arranged openings 49 provided in an annular ring plate 51 mounted on the arm 17.

As an additional feature of the present machine, I prefer to construct the standard 16 with a hinged joint 57 adjacent the upper end thereof so as to permit the movement of the plane of rotation of the arm 17 from vertical, as shown in Figure 2, to a horizontal or intermediate position. This arrangement as will be understood, provides for all of the various movements of the target explained in connection with the vertical plane of rotation of the arm 17, also in a horizontal or intermediate obliquely disposed plane. Also in order to adjust the height of the center of rotation of the arm to approximately eye level of the patient, I prefer to construct the standard 16 with telescopically engaged sections 58 and 59 for adjustably raising or lowering the center of rotation of the arm to suit various sized patients.

It will now be clear that among the various movements of the target, the same may be caused to rotate in a plurality of different sized circles varying in radius over the length of the arm by leaving the motor 39 idle and energizing the motor 22. If in addition the motor 39 is energized, the target will be caused to move both radially and circumferentially to inscribe a plurality of spiral paths. Or if the motor 22 is stopped and remains idle the arm may be set in substantially any angular position by means of the detent member 48 and the target caused to reciprocate over the length of the arm or portions thereof desired with a simple reciprocating movement. Also, as will be clear, the target in each instance of revolution of the arm 17 will be caused to automatically turn to maintain the facing and angular relation thereof constant with respect to the patient.

A further and important feature of my machine is the provision thereof for affording a stereoscopic exercising of the eyes. This exercise con-

sists in the use of a septum for separating the vision of the eyes and providing for the separate and independent exercising of the eyes along the lines hereinbefore described. The general arrangement of this feature of the invention is shown in Figure 6 of the drawings and includes a stereoscopic binocular eye piece 61, which is supported on the standard 16 by means of a vertically adjustable supporting bracket 62 and which is connected to the center of the target 18 by means of an expandable septum 63 so as to define a pair of separate target portions 18' which may be in the form of or may support stereograms or the like adapted for stereoscopic fusion. Preferably, the member 18 is in the form of a casting or frame, as illustrated in Figures 2 and 3 for the receipt of various indicia bearing cards, and stereograms and the like upon adjustment as conventional, a fusion of the targets is afforded. In order to prevent the septum from buckling or otherwise distorting during the movement of the end thereof connected to the target, the septum is preferably connected to the stationary eye piece 61 and the movable target 18 by means of horizontally and vertically pivoted members 64 which afford a modified universal connection between the eye piece and the target. Normally in the use of the stereoscopic exercise, the target 18 is moved through but a small displacement so that the expansion required by the septum 63 is but slight. Preferably the eye piece 61 is attached to the brackets 62 by means of a swivel connection 66 for enabling universality of adjustment of the eye piece with respect to the arm 17.

As previously mentioned, one of the important uses of the machine is afforded by adjusting the target 18 eccentrically of the axis of rotation of the arm and turning the plane of the target parallel to the plane of rotation, as illustrated in Figure 6, and rotating the arm while the targets 18' are under stereoscopic observation as illustrated in Figure 3. In this manner binocular fusion is obtained of the two targets in the eyes of the patient, and the targets are moved simultaneously in the same direction and to the same extent at all times through closed paths. Further, the targets are held in upright position throughout the course of their movement so that single binocular vision may be maintained. In addition, the rate of movement of the targets may be simultaneously controlled by means of a rheostat 86 in the electric circuit of the motor, see Figure 10. If at any time it is desired to vary the path of movement of the targets, the motor 39 may be energized to move the targets along the arm during rotation to inscribe spiral or other non-circular or eccentric paths generated by a combined circular and radial displacement.

As will of course be clear the binocular eye piece 61 may if desired be supported independently of the standard 16. In other instances where it is advantageous to associate phorometer head with the machine for examining the eyes with different lenses, a phorometer head may be interchanged with the stereoscopic head in the bracket 66 or supported on a similar or other mounting assembly.

In addition to the exercising of the various muscles used in connection with the moving and focusing of the eyes, I provide also in the present machine for the exercising of the muscles and nerves which control the dilation and contraction of the iris. This is here effected by causing a periodic variance of the light intensity on the target to thereby produce a resulting changing

of the light opening in the iris of the eye. In the present invention I may illuminate the target by means of a pair of lamps 67 mounted at the top of the target and which are energized as desired by means of an interrupter and control mechanism 68 here shown mounted adjacent the top of the standard 16. The mechanism 68 is illustrated in detail in Figures 9 and 10 and as here shown include a pair of electric switches each having a fixed and trip contact 69 and 71 which are arranged to be moved into and from engagement by means of a cam 72. As here shown the cam 72 is mounted for rotation on a disc member 73, driven by a motor 74, and which presents a segmental spirally shaped area for engagement with the trip contact 71 for movement thereof into engagement with the contact 69. With reference to Figure 9 it will be noted that by reason of the shape of the cam the closer the contact members 71 are moved to the center of the disc 73 the longer will be the period of contact between the contact members 71 and 69. To provide then for a variable period of closure of the electric circuit through the contacts 69 and 71 I provide for the selective advancement of the contact 71 in direction of the center of the disc. This is here provided by means of transversely extending screws 76 which are threaded through an end of the contact members 71 and which on rotation carry the contact members 71 across the face of the disc 73 on a pair of guide members 77. In accordance with the present invention the contact switches 69 and 71 are connected in series with the lamps 67 so as to periodically energize and disconnect the lamps to illuminate or darken the target. It will be noticed that by means of the individually adjustable switches the period of illumination and darkness of the lamps may be controlled independently of each other. This is of importance when used in connection with the stereoscopic exercise as it affords an individual control over the dilation and contraction of the iris of each eye. As a further feature of this arrangement, I provide through the use of rheostats 78 for the individual control of the intensity of the lamp 67 and I provide further through the use of a rheostat 79 for the speeding up or slowing down of the interrupter motor 74.

The complete electric circuit for the machine is illustrated in a schematic diagram shown in Figure 11. As here shown the electric circuit connectors 81 and 82 are brought in through the base of the standard of the machine and connected in series with a master switch 83 and with the motor 22 and the switch and rheostat therefor 84 and 86. A branch circuit defined by the connectors 87 and 88 is connected to the light control mechanism 68 and energizes the breaker motor 74 and the rheostat and switch therefor 79 and 89. The connector 87 further connects in parallel each of the breaker switches including the contacts 69 and 71 and the rheostat 78 and continues therefrom to the slip rings 91 and 92 provided on the arm 17 about the center of rotation thereof. From the slip rings 91 and 92 conductors 93 and 94 extend through the arm and to slip rings 96 and 97 provided in the carriage 35 about the target supporting shaft 27. (See Figure 4.) From the slip rings 96 and 97 conductors 98 and 99 lead through the arm 27 and to the lamps 67 mounted at the top of the target and a return conductor 101 leads from the lamp back to a slip ring 102 mounted coincidentally with the slip rings 96 and 97. From the slip ring 75

102, a conductor 103 extends to a slip ring 104 mounted coincidentally with the slip rings 91 and 92 and then back to the conductor 83 for completion of the lighting circuit. Energization of the motor 39 which causes reciprocation of the target along the length of the arm is arranged to be effected on the one side by a conductor 105 which connects at the inside of the arm to the conductor 103. The other side of the motor is connected through a rheostat and switch therefor 107 and 108 to a slip ring 109 which is mounted coincidentally with the slip rings 91, 92 and 104, and is then connected by a connector 110 to the line 82 for completion of the electric circuit therethrough.

I claim:

1. An eye exercising machine comprising, a support, an arm rotatably carried by said support, a target carried by said arm, and drive means connecting said target and arm and support for automatically turning said target relative to said arm on rotation of said arm and in a direction opposite to the direction of rotation of said arm.

2. An eye exercising machine comprising, a support, an arm pivoted thereto for rotation, motor means for rotating said arm, a target carried by said arm, means for moving said target lengthwise on said arm comprising, a screw extending lengthwise on said arm, motor means carried by said arm for rotating said screw, a carriage supporting said target and engageable with said screw.

3. An eye exercising machine comprising, a support, an arm pivoted thereto for rotation, motor means for rotating said arm, a target carried by said arm, means for moving said target lengthwise on said arm comprising, a pair of screws extending lengthwise on said arm, motor means carried by said arm for rotating said screws, means connecting said motor and screws for rotating the latter in opposite directions, a carriage supporting said target and movable into and from engagement with each of said screws alternately, and an automatically reversing mechanism arranged to hold said carriage in engagement with one of said screws for movement thereof thereover and then disengage said carriage from said screw and engage the same with the other screw.

4. An eye exercising machine comprising, a support, a member rotatably mounted on said support, a target rotatably carried by said member eccentrically to the axis of rotation of said member, and drive means connecting said target and member and support effective on rotation of said member to rotate said target in an opposite direction to the direction of rotation of said member.

5. In an eye exercising machine, a target, a supporting arm movably carrying said target, a first driving means carried by said arm and adapted when operatively applied to move said target relative to said arm in a first direction, a second driving means carried by said arm and adapted when operatively applied to move said target relative to said arm in a direction opposite to said first direction, motive means connected to impel each of said driving means, and reversing means operative to alternately successively operatively apply said first and second driving means for reciprocating said target on said arm.

6. In an eye exercising machine, a target, a supporting arm movably carrying said target,

said target being provided with engaging means adapted to engage driving means, a first driving means carried by said arm, a second driving means carried by said arm, motive means connected to impel each of said driving means, and reversing means for causing said engaging means to alternately successively engage said first and said second driving means, said first driving means being adapted when engaged to displace said target in a first direction relative to said arm, and said second driving means being adapted when engaged to displace said target in a direction opposite to said first direction.

7. In an eye exercising machine, a target, a supporting arm movably carrying said target, a first driving means carried by said arm and adapted when operatively applied to move said target relative to said arm in a first direction, a second driving means carried by said arm and adapted when operatively applied to move said target relative to said arm in a direction opposite to said first direction, motive means connected to impel each of said driving means, and reversing means operative to alternately successively operatively apply said first and second driving means for reciprocating said target on said arm, said reversing means being adjustable for actuation by the travel of said target to adjustably determined terminal positions on the path of travel of said target relative to said arm.

8. In an eye exercising machine, a target, a supporting arm movably carrying said target, said target being provided with engaging means adapted to engage driving means, a first driving means carried by said arm, a second driving means carried by said arm, motive means connected to impel each of said driving means, and reversing means for causing said engaging means to alternately successively engage said first and said second driving means, said first driving means being adapted when engaged to displace said target in a first direction relative to said arm, and said second driving means being adapted when engaged to displace said target in a direction opposite to said first direction, said reversing means comprising adjustable terminal stop means adjustably positioned along the path of travel of said target and adapted to cause said alternate engagement of said engaging means when said target has reached the positions of said stop means in its path of travel relative to said arm.

9. In an eye exercising machine, a fixed sup-

- port, an arm rotatably carried by said support, a target having indicia and being rotatably mounted on said arm, and an orienting means comprising mechanical connections connecting said arm, said support, and said target, for positively holding said target in successive positions wherein the indicia on said target occupy successive parallel positions as said target rotates with said arm.
10. An eye exercising machine comprising a fixed support, an arm, arm-rotating driving means for rotatably carrying said arm on said support, a target having indicia, target-rotating driving means for rotatably carrying said target on said arm, and coordinating means connecting said arm-rotating means and said target-rotating means for continuously rotating said target at the same rate and in the opposite sense as the rotation of said arm, whereby the indicia on said target occupy successive parallel positions on said target as said target rotates with said arm.
11. An eye exercising machine comprising a fixed support, an arm, arm-rotating driving means for rotatably carrying said arm on said support, a target having indicia, target-rotating driving means for rotatably carrying said target on said arm, coordinating means connecting said arm-rotating means and said target-rotating means for continuously rotating said target at the same rate and in the opposite sense as the rotation of said arm, a binocular stereoscopic eye-piece, and an expansible septum pivotally connecting said eye-piece and said target and positioned between the respective lenses of said binocular eye-piece and to divide said target into separate visible parts.
12. Apparatus for the treatment of the eyes, comprising a supporting frame; a target rotatably mounted thereon; an actuating motor operatively connected to said target to rotate it; a supplementary target eccentrically mounted on said first target; and means connecting said supplementary target with said frame whereby said supplementary target is held from rotation on its axis as its axis revolves about the axis of said first target, wherein said connecting means comprises an epicyclic train of gears wherein the first and last gears have the same number of teeth, carried by said first target and revolving around the fixed gear concentric with the first target.

HERMAN KATZ.
